UNITED STATES PATENT OFFICE.

LOUIS ASHLEY OSGOOD, OF CHICAGO, ILLINOIS, ASSIGNOR TO AMERICAN AUTOMATIC SCALE COMPANY, OF CHICAGO, ILLINOIS, A CORPORATION OF ILLINOIS.

WEIGHING APPARATUS.

1,402,087.

Specification of Letters Patent.

Patented Jan. 3, 1922.

Application filed June 26, 1916. Serial No. 105,903.

To all whom it may concern:

Be it known that I, LOUIS ASHLEY Osgood, a citizen of the United States, and a resident of Chicago, in the county of Cook, State of Illinois, have invented certain new and useful Improvements in Weighing Apparatus, of which the following is a specification, reference being had to the accompanying drawings.

10 My invention relates to weighing apparatus of the type involving the use of a pair of oppositely-swinging weighted arms or pendulums by which the movement of the weight-indicator is controlled. It is one of the objects of my invention to provide a new and improved form and arrangement of parts by which a maximum of sensitiveness may be secured in the movement of the indicating means. It is another object of my 20 invention to provide an apparatus of the type described involving a new and improved arrangement of the oppositely-swinging weighted arms or pendulums relative to the beam to which they are connected. 25 It is another object of my invention to provide an arrangement in an apparatus of this type by reason of which one of the weighted arms or pendulums is adapted to exert an upward pull upon the beam while the co- 30 operating weighted arm or pendulum exerts a downward pull, the cooperating weighted arms or pendulums being adapted thus to substantially offset each other so far as their dead weight is concerned while at the same 35 time being adapted to cooperate in their effective operation upon the beam. It is another object of my invention to provide a new and improved arrangement of connections between the beam and the revolvably 40 mounted hand by which the weight is indicated. It is another object of my invention to provide a new and improved arrangement of mechanism for applying a doubling weight to the beam. It is another object of 45 my invention to simplify and cheapen the construction and arrangement as far as possible, and to improve apparatus of this general type in sundry details hereinafter pointed out. The preferred means by which I 50 have accomplished my several objects are illustrated in the drawings and are herein-after specifically described. That which I believe to be new and desire to cover by this application is set forth in the claims.

55 In the drawings:

Fig. 1 is a front view of a weighing apparatus embodying my improvements;

Fig. 2 is a central vertical section taken substantially on line 2—2 of Fig. 1;

Fig. 3 is an enlarged detail, being a fragmentary view taken substantially on line 3—3 of Fig. 1;

Fig. 4 is an enlarged detail illustrating the construction and arrangement of the doubling weight mechanism, being substantially a section taken on line 4—4 of Fig. 5;

Fig. 5 is another view of the mechanism shown in Fig. 4, partly in section, taken on line 5—5 of Fig. 4;

Fig. 6 is a very much enlarged detail illustrating the means for mounting the rack-bar by which the indicating hand is actuated, being partly in section taken upon the line 6—6 of Fig. 2; and

Fig. 7 is an enlarged detail illustrating the arrangement of parts at the point where the rack-bar engages the pinion mounted upon the spindle of the indicating hand.

Referring to the several figures of the drawings in which corresponding parts are indicated by the same reference characters,—

15 indicates the framework of my improved apparatus, comprising a casing portion 16 adapted to serve as a housing for the weigh-beam and connected parts, and a drum portion 17 adapted to contain the weight-indicating means. A weigh-beam 18 is pivotally mounted upon standards 19—20 rising from the bottom of the casing 16, having connected to it means for supporting to be weighed comprising a link 21 adapted to be equipped with any approved type of platform or pan. A balancing weight 22 (see Fig. 3) is adjustably 25 mounted upon the beam 18 by means of a screw 23 by which the weight can be adjusted finely relative to the beam, an opening 24 being provided in the casing 16 for access to such screw 23. A stop device 25 of any suitable type is provided for limiting the swinging of the beam 18.

A tare-beam 26 is mounted to swing with the beam 18, being connected with the beam 18 by any suitable means extending through an opening 27 in the front face of the casing 16. The tare-beam 26 is provided with a suitable weight 28 adjustable therealong. An arm or pendulum 29 carrying a weight 30 at its lower end is fixedly mounted upon

the beam 18 is such position as to carry the weight 30 a short distance at one side of the pivots upon which the beam 18 is mounted. A second arm 31 carrying a weight 32 is pivotally mounted upon a bracket 33 extending from the inner face of the drum 17. The arm 31 has integrally formed with it a horizontally-extending arm 34 which is pivotally connected by means of a train 10 of links 35 with the beam 18 at the side of the axis upon which the beam 18 is mounted opposite to that upon which the weight 30 is located. The proportions of the weights 30—32 and their connections with the beam 15 18 are such that as the beam 18 is swung upon its pivots the effect of one of such weights in resisting the swinging movement of the beam (in the counterclockwise direction as viewed in Fig. 1) is the same as that 20 of the other weight. That is, weight 32 exerts a movement opposing counterclockwise movement of the beam, and weight 30 exerts a like movement in the same direction as does weight 32; the two weights being 25 thus in effect added together in opposing the movement of the beam by the weight of the goods on the scale-pan or platform, not shown.

By reason of having the weight 32 30 mounted so as to exert an upward pull upon the beam 18 when resisting the swinging of the beam in the direction to increase the weight indication as hereinafter described, and having the weight 30 mounted so as 35 to exert a downward pull upon the beam, the dead weight of the weight 30 is substantially offset by that of the weight 32, whereby the friction of the beam 18 upon the knife edges by which it is supported upon the standards 19—20 is greatly reduced. By reason of having the weight 30 in a comparatively low position, the stability of the apparatus as a whole is greatly increased 40 as compared to a construction in which both 45 of the weighted arms or pendulums are located above the beam.

A weight 36, for increasing the capacity 50 of the scale, is movably mounted opposite the end of the beam 18. This capacity weight is supported in position by means of a rock-shaft 37 revolvably mounted upon a bracket 38 supported by the casing 16. The arms 39—40 are fixed on said rock-shaft and are provided with pins 41—42, respectively, 55 engaging suitable grooves in the underside of a head 43 connected by means of an offset neck portion 44 with the body of the weight 36. The shaft 37 extends through the wall of the casing 16, being provided with a handle or arm 45 carrying at its outer end 60 a weight 46 which assists in holding the weight 36 in inoperative position with the centers of the pins 41—42 swung past the center of the shaft 37, as shown in Fig. 4. 65 When the arm 45 is swung in counter-clock-

wise direction in Fig. 1 the weight 36 is moved to the left in Figs. 1 and 4 bringing the sockets or grooves 47 of the weight 36 into position upon the knife 48 carried by the beam 18; the arms 39—40 carrying the pins 41—42 out of the recesses or grooves in the head 43 and having the weight 36 suspended on the said knife 48. When the arms 39—40 are swung back to normal position by means of the arm 45 the pins pick up the head 43 again and so carry the weight 36 back to its home position, shown in Figs. 1 and 4.

The proportions of the parts are such that when the weight 36 is in position upon the beam 18 an initial weight of 500 pounds is required upon the weight supporting means before the beam 18 will be swung upon its pivots. Whenever in a weighing operation the beam 18 is given a swinging movement (counterclockwise in Fig. 1) with the weight 36 mounted on the beam, it will be understood that the weight by which the beam is being actuated is equal to the weight indicated by the indicating hand as 90 hereinafter described, plus 500 pounds. For indicating the 500 pounds which must be added to the weight indication of the hand, there is provided a counter 49 pivotally mounted upon an arm 50 mounted upon the 95 drum 17, the counter being connected with the rock-shaft 37 through the medium of a link 51 which is connected by means of a link 52 to a pin 53 carried by the arm 40. Whenever the rock-shaft 37 is rotated for 100 depositing the weight 36 upon the beam 18 the counter 49 is moved downward to bring the number thereon into position to show through an opening 54 in the dial 55 carried by the drum 17.

The means for indicating the weight of goods (carried by the beam 18 through the link 21) independently of the weight indicated by the counter 49 comprises an arm 56 rising from the beam 18 carrying at its 110 upper end a yoke 57 (see Fig. 6) to which is pivotally connected a clip 58 adapted to receive a rack-bar 59 which is held adjustably in position therein by means of a set-screw 60. A weight 61 is adjustably mounted upon 115 the rack-bar 59, being held in adjusted position thereon by means of a set-screw 62. By the manipulation of the weight 61 in connection with a proper longitudinal adjustment of the rack-bar 59, the rack-bar 59 can be 120 very nicely balanced in position.

The rack-bar 59 meshes at its free end with a pinion 63 (Fig. 7) fixed upon the spindle 64 which carries the indicating hand 65 which is adapted to revolve in front of the dial 55, as is shown in Fig. 2. The forward end of the spindle 64 is supported in position by means of a suitable bearing carried by a plate 66 which is supported by means of a lug 67 (see Fig. 1) from a ring 68 car- 130

ried by the dial 55. The rear end of the spindle 64 is supported by means of a suitable bearing carried by a head 69 supported by arms 70-71 (see Fig. 1) extending inward from the ring 68. The meshing of the rack-bar 59 with the pinion 63 is controlled by a notched bracket 72 which is supported by the arm 70. As is best shown in Fig. 7, the rack-bar 59 is located below the pinion 63 and is adapted to mesh very lightly with such pinion by reason of the nice balancing of the rack-bar. The notched bracket 72 is adapted to be adjusted relative to the arm 70 so as to insure the rack-bar 59 being maintained constantly in mesh with the pinion 63 but so as to permit the engagement to be exceedingly free.

A weight 73 is mounted upon the beam 18 in adjustable position thereon for bringing the apparatus approximately into balance, the weight 22 being adapted for the finer balancing adjustments. By reason of the relative positions of the weights 30 and 32 so that one of the weights exerts an upward pull upon the beam 18, a comparatively light weight 73 suffices for bringing the scale into balance without the necessity for weighting the beam 18 heavily and thus unnecessarily increasing the friction in the knife-edge bearing of the beam.

What I claim as my invention and desire to secure by Letters Patent, is—

1. In a weighing apparatus, the combination of a pivoted weigh-beam, means for supporting an article to be weighed from said beam, means actuated by the swinging of said beam upon its pivotal mounting for indicating the weight, a rock-shaft a short distance above said beam, arms carried by said rock-shaft, a capacity weight pivotally mounted on said arms, and means for turning the rock-shaft for depositing the capacity weight upon said beam.

2. In a weighing apparatus, the combination of a pivoted weigh-beam, means for supporting an article to be weighed from said beam, means actuated by the swinging of said beam upon its pivotal mounting for indicating the weight, a rock-shaft a short distance above said beam, arms carried by said rock-shaft, a capacity weight pivotally mounted on said arms, being provided with an offset neck portion adapted to embrace said rock-shaft, and means for turning said rock-shaft for depositing the weight upon said beam.

3. In a weighing apparatus, the combination of a pivoted weigh-beam, means for supporting an article to be weighed from said beam, means actuated by the swinging of said beam upon its pivotal mounting for indicating the weight, a rock-shaft a short distance above said beam, arms carried by said rock-shaft, a capacity weight pivotally mounted on said arms, means for turning the

rock-shaft for depositing the weight upon said beam, and means actuated by the turning of said rock-shaft for giving a weight indication corresponding to the weight so deposited upon the beam.

4. In a weighing apparatus, the combination of a pivoted weigh-beam, means for supporting an article to be weighed from said beam, means actuated by the swinging of said beam upon its pivotal mounting for indicating the weight, a rock-shaft a short distance above said beam, arms carried by said rock-shaft, a capacity weight pivotally mounted on said arms, means for turning the rock-shaft for depositing the weight upon said beam, a slidably-mounted lever pivotally connected with one of said arms, and means actuated by a stroke of said lever upon the turning of said rock-shaft for giving a weight indication corresponding to the weight so deposited upon the beam.

5. In a weighing apparatus, the combination of a pivoted weigh-beam, means for supporting an article to be weighed from said beam, an arm rising from said beam, a rack-bar pivotally mounted on said arm, means for balancing said rack-bar upon its pivot, a pinion with which said rack-bar meshes lightly from below, and means actuated by the rotation of said pinion for indicating a weight.

6. In a weighing apparatus, the combination of a pivoted weigh-beam, means for supporting an article to be weighed from said beam, an arm rising from said beam, a rack-bar pivotally mounted on said arm, means for balancing said rack-bar upon its pivot, a pinion adapted to mesh with said rack-bar, means for supporting said rack-bar with its teeth barely in mesh with said pinion, means for adjusting said rack-bar supporting means relative to said pinion, and means actuated by the rotation of said pinion for indicating a weight.

7. In a weighing apparatus, the combination of a pivoted weigh-beam, means for supporting an article to be weighed from said beam, an arm rising from said beam, a rack-bar pivotally mounted on said arm, means for balancing said rack-bar upon its pivot, a pinion with which said rack-bar meshes lightly from below, means for adjusting said rack-bar vertically relative to said pinion, and means actuated by the rotation of said pinion for indicating a weight.

8. In a weighing apparatus, the combination of a pivoted weigh-beam, means for supporting an article to be weighed from said beam, an arm rising from said beam, a rack-bar pivotally mounted on said arm and adjustable longitudinally relative thereto, a weight adjustably mounted on said rack-bar for holding it substantially balanced upon its pivot, and means actuated by said rack-bar for indicating a weight.

9. In a weighing apparatus, the combination of a pivoted weigh-beam, means for supporting an article to be weighed from said beam, an arm rising from said beam, a rack-bar pivotally mounted on said arm, means for balancing said rack-bar upon its pivot, a pinion with which said rack-bar meshes from below, means actuated by the rotation of said pinion for indicating a weight, and means for substantially balancing said rack-bar relative to its support upon the beam.

10. In a weighing apparatus, the combi-

nation of a pivoted weigh-beam, means for supporting an article to be weighed from said beam, an arm rising from said beam, a rack-bar pivotally mounted on said arm, means for balancing said rack-bar upon its pivot, a pinion with which said rack-bar meshes from below, means actuated by the rotation of said pinion for indicating a weight, means for adjusting said rack-bar vertically relative to said pinion, and means for substantially balancing said rack-bar relative to its support from said beam.

LOUIS ASHLEY OSGOOD.
